Patented Mar. 10, 1914

UNITED STATES PATENT OFFICE.

SPENCER G. NEAL, OF LOS ANGELES, CALIFORNIA, ASSIGNOR TO CALIFORNIA VALVE AND AIR BRAKE COMPANY, OF LOS ANGELES, CALIFORNIA, A CORPORATION OF CALIFORNIA.

COMPENSATING VALVE.

1,089,579.

Specification of Letters Patent. Patented Mar. 10, 1914.

Application filed July 29, 1913. Serial No. 781,838.

To all whom it may concern:

Be it known that I, SPENCER G. NEAL, a citizen of the United States, residing in the city of Los Angeles, State of California, have 5 invented a new and useful Compensating Valve, (Case E,) of which the following is a specification.

The compensating valve comprised by this invention, is an improvement upon the valves 10 hitherto invented by myself, for similar use in air braking apparatus.

The present invention has among its objects to render the valve operating parts still more positive, in action, to eliminate 15 stuffing boxes and to render inner parts readily accessible upon the infrequent occasions when it is necessary to renew, repair and adjust the same.

This compensating valve combined with 20 the modified feed valve, hereinafter described, automatically compensates for loss of air through train pipe leaks or requirements therefrom during service, lap and running position, and is in this respect an 25 improvement upon the feed valve construction now in general use.

The invention consists of the various parts, combinations of parts, and details of 30 construction, all of which will be herein- 35 after described in connection with the accompanying drawing, and will then be defi- nitely pointed out in generic, and also in more specific claims.

Referring to the accompanying drawings 40 which illustrate the invention, Figure 1 is a longitudinal mid-section of the compensating valve. Fig. 2 is a mid section of the compensating valve on line x^2-a^2 of Fig. 1, showing the valve operating parts in a dif- 45 ferent position from the latter view. Fig. 3 is a view, the sectioned part of which illus- trates certain changes in the well known engineer's valve to adapt the same to co- 50 operate with this compensating valve. Fig. 4 is a plan view of a disk which is inserted in the well known braking valve to adapt same to coöperate with this compensating valve. Fig. 5 is a diagrammatic view illus- 55 trating the application of this compensating valve to a well known air braking system.

Referring in detail to the drawings:—1 is 60 the compensating valve (see Fig. 5); 2 the engineer's valve and 3 the main storage reservoir for supplying braking air to the

train. 4 is the well known main supply pipe 55 leading from the storage reservoir 3 to the brake valve 2, and 5 is the well known branch of the train pipe leading from the brake valve 2 to the main train pipe 6. Pipe 4 may be provided with the well known 60 cut-out 7. The brake valve 2 is connected with the usual equalizing reservoir 8 by means of an equalizing pipe 9. Pipe 5 is provided with a valve 11. In order to connect the compensating valve 1 with these 65 well known parts a supply pipe 12 is run from the reservoir pipe 4 to the compensating valve 1, said pipe 12 preferably being provided with a cut-out valve 14; and an equalizing reservoir pipe 15 is run from the 70 compensating valve 1 to the equalizing reservoir 8 or to the pipe 9 which is in communication with equalizing reservoir 8. Said pipe 15 is preferably provided with a cut-out valve 16. Pipe 17 is also 75 added to connect the compensating valve 1 to the main train pipe 6; said pipe 17 preferably being furnished with a cut-out valve 18.

The braking apparatus which has been de- 80 scribed relates to the engine only and it is to this part of the braking apparatus of the train that this invention pertains, but in practical operation the braking action of each car of the train is affected.

Referring now more particularly to Fig. 3, this view shows the well known engineer's 85 brake valve altered somewhat in the sectioned portion to adapt same to coöperate with this compensating valve.

22 is the usual train pipe piston chamber, the piston being removed therefrom and a combined metallic and leather gasket or disk 23 being placed over said chamber to make an air tight seal between the equalizing 95 chamber 24 of the brake valve and said train pipe chamber 22. The reason for inserting said gasket 23 is that the well known piston (not shown) which ordinarily occupies chamber 22 would not make an absolutely 100 air tight closure.

The main reservoir supply passage 25, the train pipe supply passage 26, and the train pipe connecting passage 27 are not altered from the standard equipment, but the equalizing discharge valve outlet 28 is closed by screw plug 29.

Referring now in detail to the construc-

tion of the compensating valve shown in section in Figs. 1 and 2, the casing for said valve preferably comprises an upper cap 31 having an upward tubular extension 32; and the lower cap 33. Within the casing formed by said caps 31 and 33 is a diaphragm device designated in a general way by the numeral 35, said diaphragm device comprises the diaphragm proper 36, the lower diaphragm support 37, from which depends the valve operating member or yoke 38, and also the upward extension 39 of said diaphragm device, said extension 39 playing within the guide 32 already mentioned. The upward movement of the diaphragm device 35 is limited by means of an adjustable screw 41 held in place by lock nut 42. Diaphragm 36 divides the interior of the casing into an upper chamber 43 which communicates with the equalizing reservoir 8 through the pipe 15; and the lower chamber 44 which is at all times in communication with the train pipe 6 through the branch pipe 17. Referring now to the valve proper, the release valve 45 has a winged portion 46, which travels in a valve cage 47 formed in the inner end of the conduit 48, said conduit 48 having a passage 49 which leads to the outer atmosphere. Yoke 38 already referred to is preferably made in one piece with the lower diaphragm support 37. Said yoke being united to said diaphragm support 37 by the diametrically opposite arms 38^a. At its lower end yoke 38 is provided with a horizontally extending arm 38^c, which underlies the valve cage 47 being thereby brought into alignment with the supply valve 53, so that at certain times said arm 38^c engages said valve 53 to open same. Release valve 45 has an upward extension or neck 51 terminating in a head 52. The yoke 38 carried by the valve device 35 is provided with a forked portion 38^a which passes astride neck 51 as shown. Said forked portion has a limited play between the collar 52 and valve 45. The lower end of yoke 38 extends below the valve cage 47 to impinge upon and open the supply valve 53 when the diaphragm device 35 approaches the lower limit of its movement. Valve 53 is provided with a winged portion 55 which plays within a stationary guide 56. Said valve 53 is normally held to its seat by a weak compression spring 57 seated within a hollow nut 58 screwed into the extension 59, said nut 58 is provided with a lock nut 61. Above nut 58 is a valve cage 63 which communicates with the main reservoir 3 (see Fig. 5) through passage 64 and pipe 12. The caps 31 and 33 of the casing are provided with flanged portions secured together by cap screws 65. Disk 23 (see Figs. 3 and 4) is provided with an aperture 25^a to register with supply passage 25, with an aperture 26^a to register with the train pipe supply passage 26, and with the

well known equalizing passage 70. These openings furnish outlets to all the passages and ports of the well known engineer's brake valve, the piston chamber alone being closed at its upper end and thereby separated from chamber 24.

Operation: Before describing the operation it should be recalled that this compensating valve performs all the functions of the equalizing discharge valve and its piston (said piston being dispensed with and removed from the piston chamber 22 on the engineer's valve as already stated), and in addition to such functions, this compensating valve performs certain other functions which will hereinafter be described. The engineer's valve proper will perform all of its well known functions, and maintain its various positions as before, namely, full release, running, service, lap and emergency positions. The charging of the train pipe is caused, as is well known in present braking systems of the standard type, by placing the engineer's valve in the full release position in order quickly to charge the train pipe; said engineer's valve being placed at the running position, as in present practice, as soon as the desired maximum train pipe pressure has been obtained. The train pipe having thus been charged to the required pressure and the equalizing reservoir 8, also being charged to an equality with the train pipe pressure, the result will be that the pressure in the equalizing chamber 43, which is in communication with the equalizing reservoir 8, will be the same as the train pipe pressure in the train pipe chamber 44 of the compensating valve, said chamber 44 being in direct communication with the train pipe through the pipe 17. With the pressure as just described, in order to make a reduction of the train pipe pressure the brake valve 2 is placed in the service position, thereby releasing air from the equalizing reservoir 8 to the atmosphere to any desired amount, and thus through pipe 15 releasing the pressure in the equalizing chamber 43 of the compensating valve below the pressure in the train pipe chamber 44 of said compensating valve. The result of this change of pressure will be to allow the excess pressure in chamber 44 on the lower side of diaphragm 36 to raise the diaphragm device 35 and the parts connected therewith to the position shown in Fig. 1, thus opening the release valve 45 to release train pipe air through valve cage 47 and passage 49 to the outer atmosphere. When the train pipe pressure in the train pipe chamber 44 has thus been reduced beneath the pressure in equalizing chamber 43, said diaphragm device 35 and the parts carried thereby will move back to the lap position, thus closing the release valve 44 and cutting off further escape of train pipe air. If instead of re-

ducing the pressure in the equalizing reservoir 8, as has just been described, the engineer's valve was operated in such a manner as to raise the pressure in the equalizing reservoir 8, and therefore in the equalizing chamber 43 of the compensating valve, the result would be a reverse operation of the compensating valve, the pressure in equalizing chamber 43 exceeding that in train pipe chamber 44 and causing the supply valve 53 to open, as shown in Fig. 2, thus supplying air to train pipe by way of branch pipe 12, passage 64, valve cage 63, thence past valve 53 and guide 56 to the train pipe chamber 44, out of which the air passes by way of branch pipe 17 to the main train pipe 6.

It is evident that any reduction of pressure in the train pipe chamber 44 will operate the compensating valve in the same manner as an increase of pressure in the equalizing chamber 43. Such reduction may be caused by leaks in the train pipe to supply the desired amount of air to the brake cylinder for service applications.

The adaptability of this compensating valve to furnish air pressure to the train pipe for all service applications when using the patented triple valve just referred to, eliminates the necessity for augmenting the train pipe capacity for service applications and materially reduces the element of time now required for charging the auxiliary reservoir, because air for service applications is not secured from the auxiliary reservoir for service braking.

I claim:

1. A compensating valve comprising a casing, a diaphragm device dividing the interior of casing into an equalizing chamber and a train pipe chamber, a combined outlet conduit and valve support within said train pipe chamber, a release valve operatively connected with said diaphragm to control release of air through said conduit, a supply valve to control supply of air to said train pipe chamber, and a part operated by said diaphragm to engage and open said supply valve, the engagement of said part with said supply valve occurring only when said release valve is closed.

2. A compensating valve comprising a casing, a diaphragm device dividing said casing into a train pipe chamber and equalizing chamber, and a combined outlet conduit and valve support within said train pipe chamber, a release valve operatively connected with said diaphragm to control release of air through said conduit, a supply valve to control the supply of air to said train pipe chamber, and means operated by said diaphragm to open said supply valve when the pressure in the train pipe chamber falls below that in the equalizing chamber, said valve opening means operating to

open said release valve when the pressure in the train pipe chamber rises above that in the equalizing chamber.

3. In a compensating valve, a casing, a diaphragm dividing the interior of said casing into an equalizing chamber and a train pipe chamber, a release valve to control the release of air from said train pipe chamber, a supply valve to control supply of air to said train pipe chamber, and means operatively connected with said diaphragm alternately to open said valves, said means preventing both of said valves opening at the same time and causing both of said valves to remain closed when there is a balanced pressure against opposite sides of said diaphragm.

4. In a compensating valve, a casing, a diaphragm device dividing the interior of said casing into two compartments, one of said compartments being a train pipe chamber, and the other of said compartments being an equalizing chamber, a release valve within said train pipe chamber to control the release of air therefrom, a supply valve to control the supply of air thereto, and a valve operating member operated by said diaphragm device to control said release valve, said supply valve being in the path of movement of said valve operating member to permit said valve operating member to engage and open said supply valve.

5. The combination with a train pipe and an engineer's brake valve of a compensating valve comprising a casing, a diaphragm dividing said casing into an equalizing reservoir chamber and a train pipe chamber, a conduit projecting into said train pipe chamber, said conduit at its inner end forming a valve cage, a valve in said cage to control the flow of air through said conduit, a valve operating member operatively connected with said diaphragm, there being a lost motion connection between the said valve and said valve operating member to permit a slight movement of said diaphragm before said valve is unseated, and a supply valve to supply air to the train pipe chamber, said operating member impinging upon said supply valve to open the latter immediately after the release valve has been brought to its seat.

6. The combination with a train pipe and an engineer's brake valve of a compensating valve comprising a casing, a diaphragm dividing said casing into an equalizing reservoir chamber and a train pipe chamber, a conduit communicating with the outer atmosphere projecting into said train pipe chamber, a valve cage formed within the inner portion of said conduit, a release valve in said valve cage, a valve operating device to operate said release valve, said valve operating device being operatively connected with said diaphragm and consisting of a

yoke which extends around to the side of said valve cage opposite to said diaphragm, and a supply valve at that side of the valve cage to control the admission of air from the main reservoir to said train pipe chamber, said valve device impinging upon the last named valve to open same at predetermined times.

7. The combination with the train pipe and engineer's brake valve of a compensating valve comprising a casing, a movable abutment in said casing dividing the same into an equalizing chamber and a train pipe chamber, a valve support located in said train pipe chamber, said valve support being provided with a valve cage and a passage leading from said valve cage to the outer atmosphere, a valve in said cage to control movement of air through said passage, said valve having an upward extension with a contracted portion, a yoke carried by said abutment, said yoke having arms which pass astride the contracted portion of said valve extension, a valve to control the supply of air to the aforementioned train pipe chamber, and means operatively connected with said abutment to impinge upon said last named valve to open same.

8. In a compensating valve, a casing, a movable abutment in said casing dividing the same into two chambers, means to control the air pressure upon one side of said abutment to govern the movements thereof, means to admit air to a chamber on the other side of said abutment under pressure from a supply, and to conduct air under pressure from said last named chamber to a place of use, a valve to control release of air from said last named chamber to the outer atmosphere, said valves being axially in alinement with each other and located

centrally of said abutment, and means carried by said abutment to control the operation of both said valves.

9. In combination, a casing, a movable abutment dividing said casing into a regulating chamber and a chamber in communication with the train pipe, means to control the pressure of air in said regulating chamber, an admission valve to control the supply of air to said train pipe chamber, and an exhaust valve to control the exhaust of air from said train pipe chamber to the outer atmosphere, said exhaust valve being located between the admission valve and said abutment, and means to operate said admission valve to maintain the pressure in said train pipe chamber on an equality with the pressure in said regulating chamber.

10. In combination, a casing, a movable abutment dividing said casing into a regulating chamber and a chamber in communication with the train pipe, means to control the air pressure in said regulating chamber, an admission valve to control the supply of air to said train pipe chamber, an exhaust valve to control exhaust of air from said train pipe chamber, and valve operating means controlled by said abutment to maintain a pressure in said train pipe chamber at all times equal to the pressure in said regulating chamber.

In testimony whereof I have hereunto signed my name in the presence of two subscribing witnesses at Los Angeles, in the county of Los Angeles and State of California, this 23rd day of July 1913.

SPENCER G. NEAL.
